MARKED RUBBER GOODS AND METHOD
FOR PRODUCING THE SAMEWalter L. Kauffman, 2d, Erie, Pa., assignor to
Lovell Manufacturing Company, Erie, Pa., a
corporation of Pennsylvania

Application July 11, 1932, Serial No. 621,919

3 Claims. (Cl. 101—8)

With many rubber articles it is desirable to mark the article, as for instance, with a trade mark and the present invention is designed to form such a mark so as to give a pleasing appearance and be practically permanent. The invention also contemplates a simple and effective method of producing the mark and an apparatus by which it may be readily produced. The invention further contemplates the application of the mark on wringer rolls. It is desirable to have some indication on wringer rolls by which the operator may be readily apprised of the fact that the rolls are in motion and the direction of motion. Heretofore it has been suggested to form wringer rolls of different qualities of rubber so as to contrast different portions of the roll for this purpose. In carrying out the present invention the roll is marked so as to give an indication of the direction of rotation and in carrying out this purpose the mark is preferably in the form of a symbol which may have the function of a trade mark. An apparatus is provided for producing such a mark on a wringer roll in a simple and efficient manner and in so forming the mark practicing the method involved. Features and details of the invention will appear from the specification and claims.

A preferred embodiment of the article and the manner of practicing the method is illustrated in the accompanying drawings as follows:—

Fig. 1 is a side elevation of a wringer roll with the markings shown thereon.

Fig. 2 a side elevation of an apparatus for marking the roll.

Fig. 3 a section on the line 3—3 in Fig. 1.

Fig. 4 a plan view of one of the pattern plates for marking the roll.

Fig. 5 an end elevation of a modified apparatus for accomplishing the marking.

Fig. 6 a front elevation of this apparatus.

Fig. 7 a view of the marking roll and shaft detached.

Fig. 8 a side elevation of a further modified apparatus for accomplishing the marking.

1 marks the wringer roll, 2 the shaft of the wringer roll, and 3 the marking which is placed upon the roll which may be and preferably is in the form of a symbol, or marking in the nature of a trade mark.

The apparatus shown in Figs. 2, 3, and 4 for accomplishing the marking comprises a frame 4. This has a guide track 5 over which the wringer rolls are rolled. Along the path of the guide-way are pattern plates 6 having thereon in raised portions 7 the symbols, or mark which

it is desired to impress upon the wringer roll except that the pattern is in reverse from the mark as impressed. This plate is electrically heated by any form of electric heating element 8a getting current from wires 8. The guide-way has an incoming chute 9 and above this guide-way a belt 10 is arranged which engages the rolls and advances them forward and rotatively over the guide-way and over the heating plates. The belt is carried around pulleys 11. The pulleys are 10 mounted on shafts 12. The shafts 12 are journaled in bearings 13 and one of the shafts is provided with a driving pulley 14. Along the lower reach of the belt, or that part of the belt engaging the rolls there are back plates 15 which 15 are carried by cross plates 16 and the cross plates 16 are carried by posts 17, these posts also carrying the journals 13 for the shafts.

In the operation of the apparatus as the rolls are passed over the heated pattern plates, the 20 rubber coming immediately in contact with these heated portions is slightly indented and the rubber for some depth is vulcanized to a greater extent than the surrounding rubber so that the marking can be followed below the original surface 25 face of the rubber.

In order that the marking may be definitely colored the surface of the rubber is supplied with surface sulphur. This may be accomplished by allowing a blooming rubber to bloom, or by dusting sulphur on the surface. This sulphur acting under the heat is affected so as to give it a light brown color. The action may be said to be accomplished by the burning of the sulphur and the marking being effected in the rubber by a 35 burning action, but the heat involved is not such a burning action as to seriously involve a deterioration of the immediately surrounding rubber although the mark slightly indents the surface. The effect can be accomplished by 40 heating the pattern plate to a temperature that is usually referred to as blue bordering on a straw color, such a temperature being at, or slightly above 600° F. This heat is sufficient to convert the sulphur to a rich brown color which seems to 45 incorporate itself with the rubber and become a substantially permanent coloring on the surface. There is thus impressed in the rubber a slight indentation following the pattern and a sulphur discoloration of pleasing color which is practically permanent. It enables the impression of any symbol, or mark, upon the rubber that may be desired so that in the case of the rubber wringer roll two useful functions are performed, the marked surface as a trade mark in a very 50 55

effective and attractive manner and at the same time this marking in a definite manner indicates to the operator the movement of the rolls and the direction of movement.

5 In the modification shown in Figs. 5 and 6 a frame comprises the uprights 18. Journal boxes 19 are arranged at the upper ends of these uprights and shafts 20 are journaled in these boxes. Cylindrical pattern plates 21 are fixed on the 10 shaft and have the pattern outline 22 thereon. The shaft also has rotating contacts 23 and 24 arranged adjacent to each pattern plate. The pattern plates are supplied with electric heating elements and brushes 25 and 26 operate on the 15 rotating contacts 23 and 24 and receive current from wires 27 and 28 leading to supply wires 29 and 30. Connections 31 and 32 lead from the elements of the heating plates through to the contacts 23 and 24 so as to supply current to the 20 elements and the plates and contacts are properly insulated from the shaft.

A gear 33 is fixed on the end of the shaft and this meshes with a gear 34 which is supplied with a crank 35 by means of which the shaft 20 is 25 rotated and with it the pattern plate. A driving roll 20^a is also arranged on the shaft 20 and is adapted to drive the wringer roll 1.

A rocking support 36 is pivoted on a pin 37 extending between the posts 18. It has a socket 38 30 which is adapted to receive the shaft 2 of the wringer roll. An arm 39 extends from the rock arm 36 and a link 40 extends from the arm 39 to a treadle, or similar mechanism, by means of which the rocker 36 is swung upwardly carrying 35 with it the roll into engagement with the pattern plates where the roll is rotated and receives the marking from the heat of the pattern plates acting on the rubber and the sulphur, as above described.

40 In the modification shown in Fig. 8 a frame having a guide post 41 is provided with an arm 42. A sliding support 43 is mounted on the post 41 and is carried by a cable 44 which extends over a pulley 45. The cable leads to a foot

treadle, or other device, by means of which the block 43 may be raised and lowered.

A pattern plate 46 is carried by the block 43 and the wringer roll 1 is mounted on this plate. Pattern plates 48 are arranged above the roll. 5 These are carried by links 49 extending to the arm 42. The links are pivotally connected by pins 50, the pins extending through a guide slot 51 in a downwardly extending arm 52. These pattern plates are electrically heated by interposing a heating element with suitable wiring (not shown). When the roll is put on the plate 46 it is immediately elevated into engagement with the plates 48 and these plates swing upwardly at the center and consequently position 15 themselves on the surface of the roll, so that these plates are brought together radially upon the roll and produce the marking through the heating and sulphur discoloration above described. When the block 43 is lowered, the upper 20 plates 48 open to the position shown in Fig. 8 and the roll can be readily removed from the lower plate.

What I claim as new is:—

1. The method of color-marking rubber surfaces which consists in applying to the surface a sufficient excess of sulphur and sufficient heat to permanently color the surface along the lines of a pattern desired. 25

2. The method of color-marking rubber surfaces which consists in applying through an application of sulphur to the surface a sufficient excess of sulphur and sufficient heat to permanently color the rubber along the lines of a pattern desired. 30

3. A rubber article having a distinguishing mark permanently formed thereon, the portion of the article forming the mark being indented and vulcanized to a greater extent than the surrounding rubber, the surface of said indented 40 portion provided with surface sulphur for coloring purposes.

WALTER L. KAUFFMAN, II.
